UNITED STATES PATENT OFFICE.

VIRGIL M. GRIFFIN, OF INDIANAPOLIS, INDIANA.

WORK-HOLDING LAP-BOARD.

1,059,606.

Specification of Letters Patent.

Patented Apr. 22, 1913.

Application filed January 31, 1912. Serial No. 674,487.

To all whom it may concern:

Be it known that I, VIRGIL M. GRIFFIN, a citizen of the United States, residing at Indianapolis, in the county of Marion and 5 State of Indiana, have invented a new and useful Work-Holding Lap-Board, of which the following is a specification.

The object of my invention is to produce an apparatus readily foldable into compact 10 shape, for the convenient handling, in the lap, of work such as sewing, embroidery, and the like.

The accompanying drawings illustrate my invention.

15 Figure 1 is a perspective view of the device in a completely extended condition; Fig. 2 a side elevation; Fig. 3 a plan; Fig. 4 a side elevation of the device when collapsed; Fig. 5 a fragmentary perspective of 20 a slight modification; Fig. 6 a fragmentary section of the joint between the two leaves of the lap-board; Fig. 7 a fragmentary section of one end of the primary leaf of the lap-board; Fig. 8 a horizontal fragmentary 25 section of the movable edge wall and adjacent parts; and Fig. 9 a detail of the connection between the leg members.

In the drawings, 10 indicates the board or leaf which forms the primary member of the 30 lap-board. This leaf may be formed of a single sheet of metal with the ends 11 upturned to form end boards, as indicated in Fig. 8, or may be provided with separate attached end bars 11' of wood, as shown in 35 Fig. 5. One edge of board 10 is overturned at 12 to receive a pivot 13 carried on the under face of the adjacent edge of board 10 so as to be thus held against further turning 40 movement on the pivot.

40 Secured to end bars 11 are hinges 15 the leaves 15' of which may be swung down against the end of bars 11, (or 11') so as to be stiffened thereby, being held in that 45 position by spring clips 16. Secured to the two hinge leaves 15' are the ends of a U-shaped frame 17 to which three sides of the upper open end of a bag 18 may be secured, the other side of said bag being attached to a rod 19 carried by the under face of the 50 adjacent edge of board 10.

The bag 18 may be formed with internal 55 pockets 20, for the reception of articles of various sizes and kinds, and frame 17 may carry one or more hooks 21 which are projected into the interior of bag 18 in order to detachably receive articles 22 such as needle-

books, etc. The pockets 20 may be made as a separate member detachably hung in place by hooks and eyes in the main bag 18.

Pivots secured to that member of the 60 U-shaped member 17 which is parallel to the axis of hinges 15, are supporting legs 22 each of which is preferably provided with an extension 23 readily telescoped upon the end of the leg 22. The external member of the 65 telescopic connection may be formed with a spring tongue 22' (Fig. 9) to bear upon the inner member to retain it in place. For convenience, in order to avoid loss, I attach the opposite ends of a chain 24 to the two leg 70 members 22 and 23 in such manner as to permit the separation of the leg members by an amount substantially equal to the amount one telescopes over the other.

The leaf or board 14 may be swung be- 75 neath the board 10 to the position indicated in dotted lines in Fig. 2 and there held by a spring clip 25. When the leaf 14 is thus folded, it is desirable that that edge of leaf 10 which will be nearest the user be pro- 80 vided with a retaining wall and for that purpose I provide a bar 31 extending be- 85 tween the two end bars 11, 11. Passing through the bar 31 are two rods or wires 32 which have a length sufficient to extend 85 partly across the board 10 and have their ends 33 projected into the end bars 11 so as to be pivoted therein. The opposite ends of rods 32 are carried a short distance beyond bar 31 and then bent toward each other and 90 backward and secured to bar 31, thus forming short spring sections 34 which serve to normally retain the fingers 35 beneath the upper edges of end walls 11. The tip of end 33 is bent into an eye 33' to prevent dis- 95 placement.

In order that the apparatus may be at- 100 tached to the user conveniently, with leaf 14 in either of its two positions, I attach to the board 10, near the edge farthest from the user, (conveniently to an eye 33') a cord 41 which may be carried from thence around the body of the user and then attached to a fastener 42 which is carried by leaf 14 close to the edge nearest the user. By this ar- 105 rangement board 14 may be swung to either of its positions without the necessity of re- adjustment of the cord 41, said cord serving to hold the apparatus in proper position in either position of the board 14. The work- 110 ing face of board 14 may be provided along the edge nearest the user with a measuring

scale 43 and the upper face of bar 31 also may be provided with a measuring scale.

With the apparatus in its extended position, as illustrated in Fig. 1, bar 31 may be slightly drawn toward the user so as to withdraw the fingers 35, whereupon the bar may be swung upward and away from the user to the position indicated in dotted lines in Fig. 3. Bar 31 may be padded in its under face if desired. By this arrangement the entire upper surface of the two boards 10 and 14 become available as a work holder or cutting table, the surplus material of the work being caught within the bag 18. When a smaller working surface is desired the board 14 may be swung beneath board 10 and bar 31 brought back to its normal position so that board 10 with its three sides becomes a tray which will retain material placed upon it. By pivoting the legs 22 to the yoke 17, there is sufficient freedom to permit the use of the device when the user sits in a rocking chair. This arrangement also facilitates a compact folding of the apparatus.

The entire structure may be folded into very compact shape by first swinging board 14 upon board 10, then swinging the two boards upon the hinges 15 over upon yoke 17 where they will be retained by a spring catch 45 carried by the yoke 17 attached to engage bar 31 or the adjacent edge of board 10. Leg ends 23 may then be withdrawn from the legs 22, said legs 22 being then swung upward adjacent the side arms of the U-shaped yoke 17 and the leg ends then laid at right angles to the legs 22 and the bag collapsed as shown in Fig. 4.

I claim as my invention:

40 1. A lap-board comprising a main board or leaf, a yoke hinged to one edge of said main leaf to swing thereover or in line therewith, a work holding bag suspended from said yoke, end bars erected at the ends of said main leaf, an edge bar extending between the end bars, arms carrying said edge bar and extending partially across the main leaf and pivotally attached to the end bars, and means for limiting the swing of the bag yoke relative to the main leaf.

45 2. A lap-board comprising a main board or leaf, a yoke hinged to one edge of said main leaf to swing thereover or in line therewith, a work holding bag suspended from said yoke, and means for limiting the swing of the bag yoke relative to the main leaf.

50 3. A lap-board comprising a main board or leaf, a yoke hinged to one edge of said main leaf to swing thereover or in line therewith, a work holding bag suspended from said yoke, end bars erected at the ends of said main leaf, an edge bar extending between the end bars, arms carrying said edge bar and extending partially across the main leaf and pivotally attached

to the end bars, means for limiting the swing of the bag yoke relative to the main leaf, a supplemental leaf pivoted to the opposite edge of the main leaf so that it may be swung from a position beneath the main leaf to a position in substantial alinement therewith, means for holding said supplemental leaf in substantial alinement with the main leaf, a cord secured at one end of the main leaf and of sufficient length to pass from thence around the body of the user to the opposite free corner of the supplemental leaf, and means arranged at said opposite free corner of the supplemental leaf to which the free end of the cord may be attached.

4. A lap-board comprising a main board or leaf, a yoke hinged to one edge of said main leaf to swing thereover or in line therewith, a work holding bag suspended from said yoke, end bars erected at the ends of said main leaf, an edge bar extending between the end bars, arms carrying said edge bar and extending partially across the main leaf and pivotally attached to the end bars, means for limiting the swing of the bag yoke relative to the main leaf, a supplemental leaf pivoted to the opposite edge of the main leaf so that it may be swung from a position beneath the main leaf to a position in substantial alinement therewith, and means for holding said supplemental leaf in substantial alinement with the main leaf.

5. A lap-board comprising a main board or leaf, a yoke hinged to one edge of said main leaf to swing thereover or in line therewith, a work holding bag suspended from said yoke, means for limiting the swing of the bag yoke relative to the main leaf, a supplemental leaf pivoted to the opposite edge of the main leaf so that it may be swung from a position beneath the main leaf to a position in substantial alinement therewith, means for holding said supplemental leaf in substantial alinement with the main leaf, a cord secured at one end of the main leaf and of sufficient length to pass from thence around the body of the user to the opposite free corner of the supplemental leaf, and means arranged at said opposite free corner of the supplemental leaf to which the free end of the cord may be attached.

6. A lap-board comprising a main board or leaf, a yoke hinged to one edge of said main leaf to swing thereover or in line therewith, a work holding bag suspended from said yoke, means for limiting the swing of the bag yoke relative to the main leaf, a supplemental leaf pivoted to the opposite edge of the main leaf so that it may be swung from a position beneath the main leaf to a position in substantial alinement therewith, and means for holding said supplemental leaf in substantial alinement with the main leaf.

7. A lap-board comprising a main board or leaf, a yoke hinged to one edge of said main leaf, a work holding bag suspended from said yoke, end bars erected at the ends 5 of said main leaf, an edge bar extending between the end bars, arms carrying said edge bar and extending partially across the main leaf and pivotally attached to the end bars, means for limiting the swing of the bag 10 yoke relative to the main leaf, a supplemental leaf pivoted to the opposite edge of the main leaf so that it may be swung from a position beneath the main leaf to a position in substantial alinement therewith, means for holding said supplemental leaf in substantial alinement with the main leaf, a cord secured at one end of the main leaf and of sufficient length to pass from thence around the body of the user to the 15 opposite free corner of the supplemental leaf, means arranged at said opposite free corner of the supplemental leaf to which the free end of the cord may be attached, and supporting legs pivotally carried by the unhinged edge of the bag holding yoke. 20 25
8. A lap-board comprising a main board or leaf, a yoke hinged to one edge of said main leaf, a work holding bag suspended from said yoke, end bars erected at the ends 30 of said main leaf, an edge bar extending between the end bars, arms carrying said edge bar and extending partially across the main leaf and pivotally attached to the end bars, means for limiting the swing of the bag 35 yoke relative to the main leaf, a supplemental leaf pivoted to the opposite edge of the main leaf so that it may be swung from a position beneath the main leaf to a position in substantial alinement therewith, 40 means for holding said supplemental leaf in substantial alinement with the main leaf, and supporting legs pivotally carried by the unhinged edge of the bag holding yoke. 45 50 55
9. A lap-board comprising a main board or leaf, a yoke hinged to one edge of said main leaf to swing thereover or in line therewith, a work holding bag suspended from said yoke, means for limiting the swing of the bag yoke relative to the main leaf, a supplemental leaf pivoted to the opposite edge of the main leaf so that it may be swung from a position beneath the main leaf to a position in substantial alinement therewith, means for holding said supplemental leaf in substantial alinement with the main leaf, a cord secured at one end of

the main leaf and of sufficient length to pass from thence around the body of the user to the opposite free corner of the supplemental leaf, means arranged at said opposite free corner of the supplemental leaf to which the free end of the cord may be attached, and supporting legs pivotally carried by the unhinged edge of the bag holding yoke. 60 65

10. A lap-board comprising a main board or leaf, a yoke hinged to one edge of said main leaf to swing thereover or in line therewith, a work holding bag suspended from said yoke, means for limiting the swing of the bag yoke relative to the main leaf, a supplemental leaf pivoted to the opposite edge of the main leaf so that it may be swung from a position beneath the main leaf to a position in substantial alinement therewith, means for holding said supplemental leaf in substantial alinement with the main leaf, and supporting legs pivotally carried by the unhinged edge of the bag holding yoke. 70 75 80

11. A lap-board comprising a main leaf, a yoke hinged at its ends to one edge of the main leaf to swing thereover or in line therewith, means for limiting the swing of the yoke upon the main leaf to maintain the yoke projected from the main leaf, a spring clip carried by one of said members and arranged to engage the other when the yoke is projected from the main leaf, and a work holding bag suspended from said yoke. 85 90

12. In combination, a lapboard composed of a plurality of leaves which may be folded either in line with or on top of each other, a work-holding bag, and a yoke for supporting said work-holding bag, said yoke being hinged to the lapboard so the latter may be swung over the work-holding bag to serve as a cover therefor. 95

13. In combination, a lapboard, a work-holding bag, and a yoke for supporting said work-holding bag, said yoke being hinged to the lapboard so the latter may be swung over the work-holding bag to serve as a cover therefor. 100

In witness whereof, I have hereunto set my hand and seal at Indianapolis, Indiana, this 27th day of January, A. D. 1912.

VIRGIL M. GRIFFIN. [L. S.]
